UNITED STATES PATENT OFFICE.

HARRY C. HAMES, OF LONDON, OHIO, ASSIGNOR TO THE THOMAS & ARMSTRONG COMPANY, OF LONDON, OHIO.

METAL SHINGLE.

1,073,485.

Specification of Letters Patent. Patented Sept. 16, 1913.

Application filed December 4, 1912. Serial No. 734,956.

To all whom it may concern:

Be it known that I, HARRY C. HAMES, a citizen of the United States, residing at London, Ohio, have invented certain new 5 and useful Improvements in Metal Shingles, of which the following is a specification.

The present invention has for its object to provide an improved form of metallic shingle, such as are commonly used for roofing 10 purposes.

The invention is more particularly directed to that type in which the metal shingles are joined together by means of an interlocking relation of their side edges.

15 A further object of the present invention consists in providing metal shingles with side locking means, which not only form an absolutely weather proof junction against the action of rain and snow, but will permit the desired amount of ventilation.

20 Shingles embodying the features herein set forth possess further advantages in that the side lock is formed entirely above the surface of the shingles, thus absolutely safe- 25 guarding the entrance of any water or moisture, since by this arrangement there is no trough or low place in which either might collect.

With these and other objects in view, the 30 invention consists in the construction and arrangement of parts as more fully described and set forth in the following specification and appended claim.

In order that a clear understanding of the 35 invention may be obtained, reference is made to the accompanying drawing in which similar parts are indicated by reference letters of like character, in the different views, and in which—

40 Figure 1 is an enlarged sectional view of the locking means, taken on line 1—1 of Fig. 2; Figs. 1^a and 1^b are views illustrating the manner in which the parts are applied to each other before assuming the locked

45 position of Fig. 1; Fig. 2 is an elevation illustrating several shingles assembled, as upon a roof, showing an application of the invention; Fig. 2^a is a sectional detail taken on the line 2—2, Fig. 2.

50 Referring to the drawings by reference characters, A represents the metal shingles which are substantially rectangular in form. One of the lateral edges of each shingle (the left hand edge in the illustrations) is creased 55 so as to form a groove or channel 1, having

an opening in its under side into which a corresponding portion of the adjoining shingle is adapted to register. In detail this channel is formed by bending the metal upwardly at right angles to the surface of 60 the shingle, shown at 2, from thence the metal extends horizontally, parallel to the surface of the shingle as shown at 4, forming the upper wall of the groove 1. The metal is then bent downwardly, at right 65 angles to form the side wall 5, parallel to 2, but of greater length than 2. The edge of the sheet is bent at 6, forming the lip 7 which is inclined upwardly and inwardly and against which the tongue of the adja- 70 cent shingle contacts at the point 8.

The opposite lateral edge of each shingle (the right hand edge in the illustrations) is made with an up-raised lip or tongue, formed by creasing the metal and bending 75 it to assume the shape shown at 9. Beyond the tongue 9 the metal is stamped to form the lateral corrugation 10 of substantially semi-circular cross-section, upon which the adjoining shingle rests. The edge of the 80 metal then extends in a horizontal direction in the same plane as the surface of the shingle, and terminates at a suitable distance beyond the junction in the nail flange 11 which is fastened to the boards of the roof 85 by tacks or nails 12.

In order to join the successive shingles forming one tier or row across the roof, the shingle at the extreme left is first nailed in place. The manner in which the succeeding 90 shingles are applied and locked together will be clearly understood by referring to Figs. 1^a and 1^b. In the former it will be seen the shingle to be applied is held in a position at right angles to the one already 95 in place having the wall 5 of the groove 1 resting flat on the surface of the fixed shingle. By turning the shingle downwardly about the elbow 6 as an axis, the tongue 9 enters the groove 1 (as shown in Fig. 100 1^b), and the locked position of Fig. 1 results. It is now impossible to remove the top shingle from the lower one, even though it is moved slightly to the left. The rib 9 within the groove 1 contacts 105 at 8 with the up-turned lip 7, but does not touch the wall 2 of the groove, thus allowing a slight adjustment in each shingle. Each shingle, after being locked in the proper position, is nailed down at its fur- 110

2
ther edge and successive ones applied in similar manner.

Each of the shingles is provided near its upper end with a series of three or four horizontal ribs 13, of semi-circular form. These serve to prevent the entrance of rain or moisture that might be beaten upward. The nailing flange 11 is adapted to overlap the ribs 13, and is provided with a depression 14 through which the nail is driven (see Fig. 2^a).

The lower edge of each shingle is provided with a depending flange 16 having an arch-shaped notch 17 at its middle point. 15 When the shingles are placed upon a roof they are arranged in horizontal tiers one above another, as illustrated in Fig. 2. The depending flange 16 fits snugly over the lowermost ridge 13 of the corresponding 20 shingle in the lower tier and the notch 17 bridges the wall of the groove 1, as shown.

Careful examination of this form of side lock will show that there are no raw edges of metal exposed. Furthermore there are 25 no places where flat surfaces of the metal contact, thus obviating any danger of leaks through capillary action. The points of contact are three in number, and can be designated by the point 8, the place where 30 the elbow 6 touches the surface of the shingle and the top of the ridge 10.

Having described my invention I claim:

A metallic shingle having a joint lock member at one edge thereof, consisting of a raised tongue or lip formed by creasing the metal and bending the same at an angle upwardly and rearwardly, a second ridge nearer the edge of the shingle of substantially semicircular cross section, and a nailing flange extending in the same plane as the surface of the shingle, the other edge of said shingle being formed with an overlapping member formed above the surface of the shingle, said overlapping member comprising a lateral strip of metal, extending upward from the surface of the shingle at right angles, thence horizontally in plane parallel with the surface of the shingle, thence vertically downward to a point contacting with the surface of the adjoining shingle, thence upwardly and inwardly at an angle of approximately 45° terminating at a point contacting with the surface of the raised tongue of the adjoining surface, substantially as described. 50

In testimony whereof, I affix my signature in presence of two witnesses.

HARRY C. HAMES.
